VACUUM CLEANER

Karl John Wahlborg, Stockholm, Sweden, assignor to Electrolux Corporation, New York, N. Y., a corporation of Delaware

Application July 13, 1939, Serial No. 284,203
In Germany July 13, 1938

14 Claims. (Cl. 248—26)

My invention relates to vacuum cleaners and more particularly to a support for the motor-fan unit.

An object of my invention is to provide an improved resilient support for the motor-fan unit to reduce the noise transmitted to the vacuum cleaner casing. Motor-fan units have been mounted resiliently heretofore but usually the resilient material is under compression and so transmits noise or vibrations from the motor-fan unit to the vacuum cleaner casing. The transmission of noise or vibrations through such a resilient support while partly due to the compression or clamping pressure of the supporting members is also partly dependent upon the area of contact between the unit and the supporting members.

In accordance with my invention, the compression of the resilient member is reduced and the area of contact between the unit and supporting members is reduced. The area of contact between the motor-fan unit and support is substantially a line contact.

Also in accordance with my invention the supporting members are located in or near the center of rotation of the motor-fan unit. Two supports are provided, one at each end of the unit. In order to prevent the shifting of the motor-fan unit within the support while providing the desired play, it is necessary to provide some interlocking means between the parts.

In the attached drawings, several embodiments of the invention are given by way of example. What I consider to be novel and my invention may be better understood by reference to the following specification and appended claims when considered in connection with the accompanying drawings, in which.

Fig. 1 shows the rear end of a vacuum cleaner in section, showing my improved supporting means.

Fig. 2 is a sectional view taken along the line 2—2 of Fig. 1;

Figs. 3 and 4 are views similar to Fig. 1 showing modified forms of the support;

Fig. 5 is an enlarged detail view of a part of the supporting member shown in Fig. 4;

Fig. 6 is a view similar to Fig. 1, showing a further modification in the supporting member;

Fig. 7 is a sectional view taken along the lines 7—7 of Fig. 6;

Fig. 8 is a detailed view of a part of the supporting member shown in Fig. 6;

Fig. 9 is a side view of the supporting member shown in Fig. 8;

Fig. 10 is a sectional view of the supporting means taken at right angles to the section shown at the right of Fig. 6;

Fig. 11 is a view similar to Fig. 3 showing a modified form of supporting member; and

Fig. 12 is a sectional view taken along the line 12—12 of Fig. 11.

Referring to the drawings, 10 indicates a vacuum cleaner casing in which is located a dust bag 11 and a motor 12 driving a centrifugal fan 13. One end of the casing 10 is provided with a removable cap 14 in which a discharge opening 15 is provided. Between the dust bag 11 and fan 13, a baffle 16 is mounted in the casing 10. For supporting the motor 12, two walls 17 are provided and formed of a resilient material, such as rubber.

To permit the passage of the air through or around the motor 12, walls 17 are provided with axially extending openings 18. In each of the walls 17, an opening 19 is provided for receiving the hubs 20 formed on each end of the motor 12. These openings 19 are lined with a rigid material 21 which may be metal, synthetic resin, or the like. The inner diameter of the lining 21 is slightly larger than the outside diameter of the hub 20 of the motor 12. This produces a certain amount of play. Thus, between the motor hub 20 and the lining 21, there is a free space 22 (which is greatly exaggerated in the drawings) permitting relatively free play between the parts. The lining 21 is formed as the axially extending portion of an annular ring 23 which is strengthened by a radially extending part 24. The radially extending part 24 is located on the side of wall 17 adjacent to the motor 12.

When the supporting members, or walls 17, as shown in the embodiment given by way of example, are formed as rings, it is necessary to provide securing devices to prevent relative rotation of the housing of motor 12 with respect to the walls 17. A number of different arrangements may be used, as for example, interlocking parts, but it is believed unnecessary to indicate any particular means. Due to the relatively free play between the hubs 20 and the walls 17, it may be said that the motor-fan unit 12—13 is supported by surfaces substantially in line contact.

Any axial movement of the motor-fan unit 12—13, as a result of the suction produced by the fan 13 is prevented by a contact between the ring 23 and tapered surfaces 25 provided on each end of the housing of motor 12. The supporting forces of the motor-fan unit 12—13 which

occur in the operation of the vacuum cleaner include the pressure caused by the weight of the motor-fan unit acting in a vertical direction downwardly, and the axial force resulting from the suction produced by the operation of the fan 13. As the area of the contact between the supporting members and the motor-fan unit 12-13 is small, little noise or vibration can be transmitted from the motor 12 to the outer casing 10. As shown in Figs. 1 and 2, the walls 17 may be made somewhat smaller in outer diameter than the inner diameter of the casing 10, providing a space 26 between the parts. The outer portion of the wall 17 is provided with a reinforcing ring 27 formed of rigid material. The relatively free play between the walls 17 and the casing 10 would further serve to reduce any transmission of noise or vibrations from the motor 12 to the casing 10. To prevent axial displacement of the walls 17, annular members 28 are secured within the casing 10. The intermediate wall or baffle 16 and the cap 14 also cooperate to prevent axial movement of the walls 17.

In the form of my invention shown in Fig. 3, the walls 17 have been replaced by metal springs 29 which are spaced angularly about the axis of the motor-fan unit. One end of each spring is connected to an inner ring 30, while the other end is connected to a similar outer ring 31 mounted within the casing 10. In this embodiment shown in Fig. 3, the inside diameter of the ring 30 is greater than the outside diameter of hub 20, consequently permitting relatively free play between these parts. The space between the ring 30 and the hub 20 is indicated by the numeral 32 and is greatly exaggerated in the drawings.

The ring 31 may also be provided with relatively free play in the casing 10 by a space 33. In this embodiment the contact surface between the hub 20 and the ring 30 is substantially a straight line as in the embodiment shown in Fig. 1. This is also true of the area of contact of the ring 31 in the casing 10.

In the embodiment shown in Fig. 4, two annular rings 34 of rubber or other elastic material, support the motor-fan unit 12-13 at each end. The rings 34 are secured between two rigid members 35 and 36. The two members 35 and 36 are not in contact with each other at any point. The motor 12 is provided with two conical hubs 37 which rest within the members 35. The outer members 36 are supported on shoulders 38, formed in baffles 39. The inner diameter of the member 35 is larger than the largest diameter of the conical hub 37 producing a space 40 therebetween. The space 40 permits relatively free play between the supporting member and the motor 12. Similarly, the outer member 36 is smaller in diameter than the opening in the baffle 39 where the shoulder 38 is formed. This produces a space 41 between the member 36 and the shoulder 38. The shoulder 38 is also conical in form. By providing the conical hub 37 and the conical shoulder 38, a still greater reduction in the area of contact between the hub and the supporting member and the supporting member and the baffle is produced. This further reduces the possibility of the transmission of noise or vibrations from the motor 12 to the casing 10. Instead of providing a conical hub 37 and a conical shoulder 38, it may be found desirable to form the members 35 and 36 in a conical shape, that is, by forming the two sides of these members at an acute angle to each other.

In Fig. 5, an arrangement is shown for preventing rotary movement between the housing of motor 12 and the supporting member. A pin 42 enters a recess 43 provided in the supporting member 34. The pin 42 is secured to the baffle 39. A similar pin 44 is secured to the motor 12 and extends into a recess 45 provided in the supporting member 34. The recesses 43 and 45 are considerably larger than the pins 42 and 44 to provide a relatively loose connection under ordinary working conditions. The same result may be obtained in preventing the rotation of the housing of motor 12, simply by providing a projection on one part engaging in a corresponding recess on the other part.

In the form of my invention illustrated in Figs. 6 to 12, two transverse walls 46 and 47 are secured within the casing 10. Walls 46 and 47 are provided with openings 48 forming an air passage therethrough. Centrally of the walls 46 and 47 are inturned flanges 49 and 50 respectively, defining central openings 51 and 52. The motor 12 is provided at each end with a hub 53. Between the hubs 53 and the flanges 49 and 50, supporting discs 54 are provided, formed of a resilient material, such as rubber. Inner rigid rings 55 are located between the hubs 53 and supporting members 54. Outer rings 56 of rigid material are located between the supporting members 54 and the flanges 49 and 50. The rings 55 are provided with inwardly extending flanges 57 engaging the ends of hubs 53 and the outer rings are provided with outwardly extending flanges 58 engaging the baffles 46. The flanges 57 and 58 prevent axial movement of the supporting members 54. Between the rings 56 and the flanges 49 and 50, a space 59 is provided to permit relatively free play between the parts. A similar space 60 is provided between rings 55 and hubs 53, as shown somewhat exaggerated in Fig. 7. By the provision of the spaces 59 and 60, the motor 12 is supported with a substantially line contact between the hubs 53 and the rings 55, and between the rings 56 and flanges 49 and 50.

As best indicated in Figs. 8 and 9, the two faces of the discs 54 are provided with approximately hemispherical projections 61. At diametrically opposite sides of each face, two elongated projections 62 are provided. One projection 62 on each face is provided with a slot 63. The slotted projections 62 are staggered with respect to each other on opposite faces. Each of the radially extending parts of the rings 55 and 56, overlying the supporting discs 54, is provided with a tongue 64 entering slot 63, as indicated in Fig. 10. The top outside and inside edges of the discs 54 are provided with flats 65 and 66. The rings 55 and 56, the hubs 53, and the flanges 49 and 50 are provided with corresponding flats to cooperate with the flats 65 and 66. The flats 65 and 66 prevent relative rotary motion between the housing of motor 12, supporting members 54 and the baffles 46 and 47. The relatively thin supporting discs with play between the supporting member and the motor 12 and baffles 46 and 47 results in a relatively small area of contact between the parts with the free play therebetween which reduces the amount of noise or vibrations that may be transmitted from the motor 12 to the casing 10.

In Figs. 11 and 12, a modified form of supporting disc 67 is shown with spaced annular projections 68 and 69 on the two faces. The contact between supporting discs 67 and the rings

55 and 56 consists of two concentric circular lines. The opposite faces of the disc 67 are provided with radially extending slots 70 and 71 spaced 180° apart on the two opposite faces. The slots 70 and 71 are adapted to receive the tongues 64.

While the invention has been described in connection with several embodiments, it is to be understood that the invention is not limited to the particular embodiments shown, but may be varied within the scope of the appended claims.

What I claim is:

1. An electric motor support including a motor, a casing surrounding said motor, a ring of resilient material interposed between said motor and said casing, an outer ring of substantially rigid material surrounding said ring of resilient material, and an inner ring of substantially rigid material located between said motor and said ring of resilient material, said inner ring having relatively free radial play with respect to said motor.

2. An electric motor support including a motor, a casing surrounding said motor, a ring of resilient material interposed between said motor and said casing, an outer ring of substantially rigid material surrounding said ring of resilient material, and an inner ring of substantially rigid material located between said motor and said ring of resilient material, said outer ring having relatively free radial play with respect to said casing.

3. In a vacuum cleaner, a casing, a motor located in said casing, a disc of resilient material having an opening to receive one end of said motor and projections from each face, a ring of substantially rigid material abutting the projections of one face and surrounding the outer periphery of said disc, and a second ring of substantially rigid material abutting the projections of the opposite face of said disc and extending between said motor and said disc.

4. In a vacuum cleaner, a casing, a motor located in said casing, an annular ring of resilient material supporting said motor in said casing having projections from each face and radially extending slots, a ring surrounding the outer periphery of said annular ring and having a tongue engaging in one of said slots, and an inner ring located between said motor and said annular ring having an inwardly extending tongue engaging in another of said slots.

5. An electrical motor support including a motor, a casing surrounding said motor, a ring of substantially rigid material surrounding a portion of said motor and being of greater diameter than the diameter of the portion of said motor, a second ring located within said casing and being of smaller external diameter than the diameter of the adjacent portion of said casing, and resilient supporting means interposed between said first-named ring and said second-named ring whereby said motor is free to move radially within said first-named ring without opposing force, and said second-named ring is adapted to move radially within said casing without opposing force.

6. A casing, a motor located in said casing, an annular body of resilient material adapted to support said motor in said casing and having projections on one of its faces, a substantially rigid member located between said body and said motor, and a second substantially rigid member located between said body and said casing, one of said members engaging the projections of

said body, said members being positioned so as to transmit the axial thrust of the motor through the projections of said body to the casing.

7. A motor, a support, and resilient mountings having means to receive end portions of the motor adapted to hold the motor in position with respect to the support, shoulders on the motor between the mountings adapted to engage said mountings to prevent endwise displacement of the motor, the distance between the shoulders being less than distance between the mountings by a space sufficient to permit a substantial amount of unrestrained free play between said casing and the support.

8. A motor body, a supporting body, a cylindrical motor mounting member, a supporting mounting member having a cylindrical opening, said first member being of smaller diameter than the opening in said second member and adapted to rest within the opening in said second member and be supported thereby, said first member being adapted to support the motor body, and said supporting body being adapted to support the second member, and resilient means interposed between said second member and said supporting body, the difference in the diameters of the cylindrical surfaces of the mounting members being such as to permit a substantial amount of unrestrained free play between the mounting members, said mounting members being composed of hard rigid material to reduce the area of contact therebetween substantially to a line.

9. A motor body, a supporting body, a conical motor mounting member, a supporting mounting member having a conical opening, the acute angle between the conical surface of the first member and the axis thereof being greater than the acute angle between the conical surface of the opening in the second member and the axis thereof, said first member being adapted to rest within the opening in the second member and be supported thereby, said motor being adapted to be supported by said first member and said second member being adapted to be supported by said supporting body, and resilient means interposed between one of said members and the corresponding body, the difference between said acute angles and the displacement between the apexes of said conical surfaces being sufficient to permit a substantial amount of unrestrained free play between the mounting members.

10. A motor comprising a stationary member and a horizontal rotor, a member for mounting the motor, a resilient body interposed between said members supporting the motor on the mounting member against movement perpendicular to the axis of rotation of the rotor, a face on the surface of one of said members having a substantial projected area in a plane perpendicular to the axis of rotation of the rotor, a plurality of projections on the surface of said body abutting said face to transmit the axial thrust of the motor to the mounting member, said projections being easily deformable in the direction of the motor thrust compared to the deformability of the main portion of said resilient body.

11. A motor having a rotor and a stator, a mounting, and means to support the motor on the mounting comprising a member of resilient material, said means being in engagement with said motor and supporting it ultimately against motion in all directions perpendicular to the axis of rotation of the motor while permitting a substantial amount of unrestrained free play in said

directions, said member having projections adapted to receive the axial thrust of said motor and transmit it to the mounting, said projections being easily deformable in the direction of said axial thrust compared to the deformability of the main body of the member.

12. A motor having a stator and a rotor, a hollow casing surrounding the motor, a resilient mounting interposed between the motor and casing, said mounting having an open space receiving a portion of the motor, the open space within said casing receiving a portion of the mounting, at least one of said open spaces being of substantially larger size than the portion received therein to provide a substantial amount of unrestrained free radial play between the motor and the casing.

13. In a device of the class described, a motor member, a support member, a resilient mounting holding the motor in position with respect to said support, said mounting including a resilient element having an opening therethrough and

inner and outer surfaces and rigid material secured to one of said surfaces, said rigid material having substantially line contact with one of said members for transmitting force from said motor member to said support member, there being a substantial amount of unrestrained free play between said rigid material and said one of said members.

14. In a device of the class described, a motor member, a support member, a resilient mounting holding the motor in position with respect to said support, said mounting including a resilient element having an opening therethrough and inner and outer surfaces and rigid material secured to one of said surfaces, said rigid material having substantially point contact with one of said members for transmitting force from said motor member to said support member, there being a substantial amount of unrestrained free play between said rigid material and said one of said members.

KARL JOHN WAHLBORG.
